[57] CLAIM

The ornamental design for a welding lens assembly, as shown and described.

DESCRIPTION

FIG. 1 is a front view of the welding lens assembly;
FIG. 2 is a top view;
FIG. 3 is a bottom view;
FIG. 4 is a back view;
FIG. 5 is a right side view of the welding lens assembly relative to the illustration of FIG. 1, and the left side view is the mirror image of FIG. 5;
FIG. 6 is a front view of an alternate embodiment of welding lens assembly;
FIG. 7 is a top view of the alternate embodiment of welding lens assembly;
FIG. 8 is a bottom view;
FIG. 9 is a back view;
FIG. 10 is a right side view of the alternate embodiment of welding lens assembly relative to the illustration of FIG. 6;
FIG. 11 is a left side view of the alternate embodiment of welding lens assembly relative to the illustration of FIG. 6;
FIG. 12 is an isometric view of the welding lens assembly illustrated in FIGS. 1-5; and,
FIG. 13 is an isometric view of the alternate embodiment of welding lens assembly illustrated in FIGS. 6 and 11.

FIG. 2

FIG. 1

FIG. 3

FIG. 5

FIG. 4

FIG. 7

FIG. 6

FIG. 8

FIG. 10

FIG. 9

FIG. 11

FIG. 12

FIG. 13
